UNITED STATES PATENT OFFICE.

HERSCHEL M. CONNER, OF CHICAGO, ILLINOIS, ASSIGNOR TO UNIVERSAL HYDRO-CARBON GAS COMPANY, A CORPORATION OF DELAWARE.

DESIGN FOR A LIGHTING-FIXTURE.

41,348.

Specification for Design.

Patented May 2, 1911.

Application filed February 23, 1910. Serial No. 545,545. Term of patent 14 years.

To all whom it may concern:

Be it known that I, HERSCHEL M. CONNER, a citizen of the United States, and resident of Chicago, county of Cook, and State of Illinois, now temporarily residing in Washington, District of Columbia, have invented a new, original, and ornamental Design for Lighting-Fixtures, of which the following is a specification, reference being had to the accompanying drawing, forming a part hereof.

The figure in the accompanying drawing is a perspective view of a lighting fixture showing my new design.

The essential features of the design are the upper body, the globular member at the lower end of the same, the ring section depending from said globular member, and the connection extending from the globular member to the bottom of the ring section.

I claim:

The ornamental design for a lighting fixture, as shown and described.

HERSCHEL M. CONNER.
